US0D1111442S

(12) **United States Design Patent** (10) **Patent No.:** **US D1,111,442 S**
(45) **Date of Patent:** **** Feb. 10, 2026**

(54) **STORAGE BOX**

(71) Applicant: **Zhejiang Xinding Plastic Co., Ltd.**,
Taizhou (CN)

(72) Inventors: **Shangqi Ai**, Taizhou (CN); **Xin Jin**,
Taizhou (CN); **Zhidong Wang**, Taizhou
(CN)

(73) Assignee: **Zhejiang Xinding Plastic Co., Ltd.**,
Taizhou (CN)

(**) Term: **15 Years**

(21) Appl. No.: **29/991,581**

(22) Filed: **Mar. 1, 2025**

(30) **Foreign Application Priority Data**

Sep. 4, 2024 (CN) 202430565027.X

(51) **LOC (15) Cl.** **03-01**

(52) **U.S. Cl.**

USPC **D3/273**; D6/667; D6/671

(58) **Field of Classification Search**

USPC D3/273, 276, 282, 283, 304, 305, 307,

D3/308, 309, 310, 311, 312, 313, 314,
